TUFTING MACHINE

David Brown, Brooklyn, N. Y.

Application March 29, 1950, Serial No. 152,627

1 Claim. (Cl. 45—138)

1 This invention relates to a machine for upholstering furniture and particularly for the production of tufted cushions, seats and the backs for sofas, studio couches and the like.

In the art of upholstering furniture it is customary to compress the material at given points from the top and bottom of the material and then tying the material together by applying a button on top and a button on the bottom at the point of compression and tying the individual buttons by hand.

An object of this invention is to provide a machine whereby upper and lower button members are gripped and carried toward each other by magnetic grip members which are arranged to be moved toward or from each other and whereby, when the magnetic grip members are forcibly brought together, the upper and lower parts of the button are clinched or assembled in unitary relation and thereby hold the upholstering material in the desired relation.

Another object of this invention is to modify an upholstery tufting machine by securing apertured positioning guideways to the lower portion of the tufting machine, the apertures being in alignment with the button tubes in the tufting machine, and to provide a roller mounted portable press having magnetic plungers adapted to grip and hold coacting button elements, the press having means whereby the magnetic plungers are aligned by the positioning apertures with the button tubes, and having means for moving the plungers toward each other, whereby the button elements are pressed into assembled relation to hold the fabric sections together.

With the above and other objects in view, the invention will be hereinafter more particularly described, and the combination and arrangement of parts will be shown in the accompanying drawings and pointed out in the claim which form part of this specification.

Reference will now be had to the drawings, wherein like numerals of reference designate corresponding parts throughout the several views, in which:

Figure 1 is a top plan view of an upholstery tufting machine to which my invention is applied, both the tufting base plate and the slideable plate of the tufting machine being broken away to show a top plan view of a perforated plate and guideway forming plates.

Figure 2 is a top plan view of a portable foot press having upper and lower magnetic grip members for assembling and clinching metallic button members to hold the upholstering mate-

rials held in tufting relation in the upholstery tufting machine shown in Figure 1.

Figure 3 is a side elevation of the magnetic press, the press frame being partly broken away to show operating levers,

Figure 4 is a cross-sectional view of the tufting machine shown, the section being taken on line 4—4 in Figure 1.

Figure 5 is a central cross-sectional view of a motor driven rotary cutter for cutting out tubular openings in which the button elements are positioned for assembly.

Figure 6 is a central cross-sectional view of two coacting metallic button elements held in alignment by the magnetic grip members shown in Figure 3.

Figure 7 is an assembly view of the two button elements, shown in Figure 6 and in gripping relation with fabric sections.

Figure 8 is a central cross-sectional view of two coacting metallic button elements, the lower element being a washer.

Figure 9 is an assembly view of the two button elements shown in Figure 8 and in gripping relation with fabric sections.

Figure 10 is a view of a fragmentary portion of the rotary cutter shown in Figure 5, on an enlarged scale.

In the illustrated embodiment of the invention, the numeral 10 indicates an upholstery tufting machine having my invention applied thereto. The tufting machine 10 comprises a base plate 11 having hollow tufting tubes 12 mounted thereon in linearly spaced-apart relation. The tufting tubes 12 are positioned in rectangularly spaced-apart relation but may be arranged in diamond shaped form, etc. At each end of the base plate 11 are two elongated guide rods 13 having stop collars 14 positioned in spaced-apart relation from the base plate. A plate 15 is slidably mounted on the guide rods 13 and when the tufted material is compressed, the slideable plate rests on the stop collars 14.

The base plate 11 is pivotally mounted on a portable frame comprising upright legs 16 which converge at their upper ends in bearings 18 through which extend stub shafts 19 fixed to the base plate 11. At their lower ends, the legs 16 are connected by pipes 17 extending the full length of the machine. Lock pins 20 pass through the bearings 18 and extend into the stub shafts 19 and maintain the base plate in fixed horizontal position. The legs 16 are preferably mounted on swivel casters 21.

Figure 4 shows a portion of the tufting machine

10 having filling material 22 compressed around tufts 23 formed in fabric 24 and 25, shown in cross-section. Instead of following the usual practice of using breakable twine for manually tying tufting buttons on opposite sides of the tufted fabric, I employ a portable button press 30 for interlocking upper and lower metal button elements 31 and 32 on opposite sides of tufted fabrics 24 and 25 to produce tufted upholstery in which the tufts are not separable because the interlocked button elements cannot break apart.

The portable button press 30 comprises an inverted V-shaped upright rear wall 35 having integral horizontal base extensions 36 movably supported on swivel casters 37.

The button press 30 also comprises an integral horizontal guide arm 38 positioned above the base extensions 36. At the free end of the arm 38 is mounted a positioning or pilot pin 40 having an integral collar 41 on which is a coil spring 42 which normally lowers the positioning pin 40 below the arm 38.

A link 43 is pivotally mounted on a bearing pivot 44 and has a slotted front end 45 in engagement with a pin 46 at the upper end of the positioning pin 40. At its rear end, the link 43 is connected by a pin 47 to a link 48 which is pivotally mounted on a bearing pin 49. The link 48 has a slotted rear end 50 where it is pivotally connected to a pin 51 at the lower end of a vertical link 52 having a lever 53 suitably connected thereto at its upper end.

The button press 30 has an arm 55 at its upper elevation providing a mounting for a vertically movable plunger 56 and an arm 57 at a lower elevation providing a mounting for a vertically movable plunger 58.

A foot-pedal 60 is pivotally mounted on a bearing pin 61 suitably supported at the lower elevation of the press. A lever 62 has its lower end pivotally connected on a pivot pin 63 at the rear portion of the foot-pedal 60.

The upper end of the lever 62 has a pivot pin 64 movable in a slotted end 65 of a lever 66 which is pivotally mounted on a bearing pin 67. The front end of the lever 66 is slotted and carries a pivot pin 68 extending from the upper end of the plunger 56.

In operation of the combined upholstery tufting mechanism, the operator pulls down the lever 53 to raise the positioning or pilot pin 40. The operator then pushes the button press 30 toward the tufting machine 10 so that the guide arm 38 on the press moves between two guide bars 70 on the tufting machine. The guide arm 38 and the guide bars 70 have pointed or V-shaped front ends to facilitate entrance of the guide arm between the guide bars. This guides the button press in direction of the guide apertures 71 in guideways 72 in a positioning plate 73 on the tufting machine.

The operator then releases the lever 53 to permit the positioning pin 40 to snap into a guide aperture 71. The plungers 56 and 58 are then in alignment with one of the tufting tubes or button tubes 12 on the tufting machine 10. The operator presses down the foot pedal 60 and moves the plungers 56 and 58 simultaneously toward each other to assemble the upper and lower button elements 31 and 32. The operator then lowers the lever 53 to raise the positioning pin 40 and moves the button press 10 to the next guide aperture 71 and repeats the button interlocking or riveting operation.

It is to be noted that the spacing of the guide

apertures 71 in the plate 73 corresponds to the spacing of the tufting tubes 12 in the tufting machine 10. It is also to be noted that the upper and lower magnetic plungers 56 and 58 hold the upper and lower metal button elements 31 and 32 for the assembling operation. While the plunger magnets may be made of permanently magnetized or highly magnetic metal, it is to be noted that the magnetic effect may be produced by electromagnetic means.

A hand carried electric drill having a chuck 75, Fig. 5, supports a hollow rotary cutter 76 having a tapering knife-shaped lower edge 77, Fig. 10. The hollow cutter has an outlet aperture 74 at its upper end through which the waste material cut from the fabric is discharged. The waste material falls into a funnel 78 which is secured at the upper end of a hollow sleeve 79 in which the rotary cutter 76 is housed. In the funnel is a coil spring 80, the upper end of which terminates in an inverted cup-shaped closure member 81. The closure member is vertically slidably mounted in a sleeve 82, the lower portion of which is secured such as by soldering, to the funnel 78.

The operation of the chuck 75 and cutter 76 is controlled by the button tubes 12 on the tufting machine 10. The rotary cutter 76 perforates the upholstery fabric to receive the shanks of the button elements. This perforating operation is done before the button press 30 is brought into action.

It is to be noted that, as shown in Figures 6 and 7, the upper button element 31 has a hollow shank 85. It is also to be noted that the button element 35 has a centrally and upwardly pointed shank spreader 86. When the button elements 31 and 32 are brought together, the shank spreader 86 spreads the lower edge portion of the shank 85 outwardly so as to engage the peripheral edge defining the central aperture 87. This operation produces the assembled metallic cloth covered or plastic composition covered tufting button 88.

As shown in Figures 8 and 9, there is provided modified metallic button elements 31 and 89. The button element 89 is in the form of a washer and is supported at the upper portion of a hollow casing 90 which has a shank spreader 91. The spreader 91 spreads the lower edge portion of the shank 85 outwardly into engagement with the fabric section 25. This operation produces the assembled metallic button 92.

The washer 89 is used when the tufted material 25 is coarse, such as burlap, cardboard or wood. The button 88 is used when both tufting materials are of finished tapestry materials, that is, when both sides of the tufted materials are face materials and have buttons to match the colors, etc.

In operation, the base plate 11 and the slideable plate 15 are held in tufting position by a C-clamp 93, well known in the art.

In accordance with the patent statutes I have described and illustrated the preferred embodiment of my invention, but it will be understood that various changes and modifications can be made therein without departing from the spirit of the invention as defined by the appended claim.

I claim:

70 The combination of an upholstery tufting device for pressing two coating metallic button elements into interlocked relation with one another to hold tufted fabric sections together including a base plate with a series of button tubes depending therefrom and arranged in parallel rows

spaced from one another and a horizontal positioning plate means having apertures arranged correspondingly to the respective button tubes with guideways extending along beside the rows of apertures, and of a press device for pressing the button elements into interlocked relation with one another including plunger elements vertically alignable with the button tubes and a horizontal guide arm extendable between the guideways of the tufting device horizontal positioning plate means and having pins adapted to releasably engage one at a time the respective positioning apertures of the positioning plate means, one of said devices being horizontally adjustable with

respect to the other, whereby the press plungers may be readily aligned with the button tubes.

DAVID BROWN.
